US00D980994S

(12) **United States Design Patent** (10) Patent No.: **US D980,994 S**
(45) Date of Patent: **** Mar. 14, 2023**

(54) **SCALP TREATMENT APPARATUS**

(71) Applicant: **LG ELECTRONICS INC.**, Seoul
(KR)

(72) Inventors: **Sanghoon Yoon**, Seoul (KR); **Minji Seo**, Seoul (KR); **Gayeong Lee**, Seoul (KR)

(73) Assignee: **LG ELECTRONICS INC.**, Seoul (KR)

(**) Term: **15 Years**

(21) Appl. No.: **35/512,209**

(22) Filed: **Jan. 20, 2021**

(80) **Hague Agreement Data**

Int. Filing Date: **Jan. 20, 2021**

Int. Reg. No.: **DM/212551**

Int. Reg. Date: **Jan. 20, 2021**

Int. Reg. Pub. Date: **Jul. 23, 2021**

(30) **Foreign Application Priority Data**

Aug. 6, 2020 (KR) 30-2020-0036738

(51) **LOC (14) Cl.** **28-03**

(57) **CLAIM**

The ornamental design for a scalp treatment apparatus, as shown and described.

DESCRIPTION

1. Scalp treatment apparatus

1.1 : Perspective

1.2 : Front

1.3 : Back

1.4 : Left

1.5 : Right

1.6 : Top

1.7 : Bottom

The broken lines indicate portions of the article that form no part of the claimed design. The portion of the design shown in the color grey in Figures 1.2-1.5 and 1.7 is for the purpose of illustrating portions of the scalp treatment apparatus that form no part of the claimed design.

1 Claim, 7 Drawing Sheets
